UNITED STATES PATENT OFFICE.

BARNEY GRONKE AND CHARLES F. CRUMB, OF CHICAGO, ILLINOIS, ASSIGNEES TO
INTERNATIONAL HARVESTER COMPANY, OF CHICAGO, ILLINOIS, A CORPORATION
OF NEW JERSEY.

EXTENSION ELEVATOR FOR POTATO DIGGERS.

Application filed January 10, 1924. Serial No. 685,333.

This invention relates to potato diggers of the elevator type. Under certain conditions it is desirable to use an auxiliary conveyer as an extension of the main conveyer or elevator carried by the digger, and the principal object of this invention is to provide an auxiliary elevator that will be readily attachable to the upper end of a digger body and which will be so constructed that it will be rigidly and securely held in proper position and, at the same time, be free of cross members or arches connecting the upper edges of its side plates as was heretofore found necessary, which members were objectionable because of obstruction they furnished to free travel of the vines, etc., raised by the digger.

A further object is to provide a construction in which the side plates of the extension elevator are reinforced by bars of special form, the upper ends of which are made to serve as points of attachment for the adjusting mechanism of the extension.

The invention accordingly resides in the organization and details of construction, or equivalents thereof, hereinafter described and more particularly defined in the claims.

Referring to the drawings accompanying the application,—

Fig. 1 is a side elevation of a rear portion of a potato digger with the supporting axle and drive shaft in section and with the elevator extension shown in position;

Fig. 2 is a plan view of the rear end of a potato digger with the elevator extension in position;

Fig. 3 is a vertical section through the elevator extension with the conveyer omitted;

Fig. 4 is a detail view of one of the hinge members connecting the extension to the digger;

Fig. 5 is a detail view of the bracket with which the hinge members cooperate;

Fig. 6 is a detail view showing the hinge member and bracket of Figs. 4 and 5 assembled; and

Figs. 7 and 8 are plan and edge views, respectively, of a retaining clip used to connect the hinge member and bracket.

The illustrative device is shown in connection with an elevator type of digger comprising generally the longitudinally extending side sills 10 which carry the side plates 11 and the rear or upper ends of which are

supported on the axle 12 journaled in the bearing brackets 13, which are secured under the sills in any suitable manner. The axle 12 is supported on the carrying wheels 14 and serve to drive the upper or main conveyer shaft 15 by means of drive gears 16 fixed thereon and meshing with drive pinions 17 on the ends of shaft 15. The sills 10 carry a transversely extending seat supporting arch 18, which is preferably braced by diagonally extending members 19, as shown in Fig. 1. The shaft 15 has the usual conveyer sprockets 20 fixed thereto over which is trained the endless rod-link elevator or conveyer 21, which passes over suitable sprockets at the lower end of the digger, (not shown), and preferably has its lower run passing over supporting rollers 22 on the under sides of the sills.

The construction so far described is conventional and forms no part of the present invention except as it cooperates therewith.

The extension elevator shown comprises side plates 23 which are comparatively wide at their forward ends and taper toward the rear. The longitudinal edges of the plates 23 are flanged by bending the edges of the plate out as at 23' to give them rigidity and the lower edges of the plates are connected by brace members 24. Near the lower edges of the plates adjacent and at their rear ends there is journaled a drive shaft 26 carrying sprockets. Two sprockets at the front of said plates rotate on trunnions held in place by the rod 25, these sprockets carrying the conveyer 27. The drive shaft 26 carries a sprocket pinion which is connected by drive chain 28 to a sprocket pinion on the shaft 15 from which the shaft 26 is driven. Side extension plates 29 serve to guide the material toward the ground and are preferably provided at the rear ends of each side plate. The means shown for mounting the extension on the digger comprises the hinge members 30, one of which is secured to the forward ends of each plate 23 by means of longitudinally extending strap portions 31 bolted or otherwise secured to the outer faces of the respective plates. Each member 30 is formed with an inwardly offset bearing-head 32 preferably integral with the strap portion 31. This bearing-head is of the forked type and is formed to embrace, and pivot on, inward extensions of the journal brackets for the

105

shaft 15 of the digger inside the plane of the plates 23. The journal brackets carrying the upper conveyer shaft 15 of the digger include integral extensions comprising radial 5 arms 33 and 34, which are spaced apart approximately 90 degrees and connected at their outer ends by an arcuate guide track 35. The bearing brackets which carry shaft 15 are secured directly beneath the upper 10 ends of the sills 10 and the offset bearing-heads 32 of the hinge members fit on sleeve extensions thereof at the inner sides of the bracket-heads and in contact with (as shown in Figs. 4 and 6) the arcuate guide track 15 35 engaging the outer sides of the strap portions 31 at a point intermediate their lengths. In order to retain the elevator extension in position, each of the strap members 31 has secured thereto a detachable clip 20 36 which has a body portion adapted to be secured to the hinge member at a point between the arms 33 and 34 and inside of the track 35 and be retained there as by a bolt 37. This clip has an offset lip 36^a which 25 overlaps and engages the outer side of the arcuate track 35 in a manner to permit free sliding movement of the hinge member on said track as the elevator extension is adjusted about its pivot. This construction retains the hinge in position on its support 30 and also prevents lateral movement.

It will be evident that the interlocking relation of the hinge members 30 with the guide portions 35 and the bracket sleeves on shaft 15 affords a construction which retains the elevator firmly in position and at the same time braces and strengthens the forward portions of the side plates 23. As further reinforcing means for the plates there 40 are provided reinforcing bars 38 secured to the outer faces of each of the plates. Each of these bars extends from a point at the upper forward edge of the plate 23 rearwardly and downwardly in a diagonal direction 45 across the face of the plate. Preferably, each bar 38 extends for a distance substantially parallel to and adjacent the upper edge of the plate 23 and then is angled to extend downwardly to a point near the lower 50 edge of the plate and about half way between its ends. This construction in conjunction with the strap 31 efficiently reinforces and braces the side plate and eliminates the necessity for any connection between the upper 55 edges of the two plates 23. As adjusting means for the extension, the seat supporting arch 18 carries a transverse shaft having a lever 39 secured thereto. Each end of this shaft is provided with a crank 60 40, and rods 41 connect these cranks with collars 42, which are pivoted to the forward ends of the reinforcing bars 38. Each rod 41 is preferably made adjustable in the collars 42, as by means of stop nuts 43 threaded 65 on the end thereof.

It will be plain that, with the simple construction described, the elevator extension can be readily detached and that, while in position on the digger, the extension will be firmly retained in any desired position of adjustment, the reinforced side plates requiring no tie rods or braces between their edges as heretofore found necessary. It is also to be noted that the novel hinge connection disclosed is not limited to the particular elevator extension shown, but is capable of use with any pivoted attachment or extension on the rear of the digger. 70

The structure above described exemplifies the preferred form of the invention, but variations in details of construction are possible and may be made within the scope of the following claims. 80

What is claimed as new is:

1. In potato diggers, the combination with the upper conveyer shaft of a digger of an extension conveyer comprising side plates carrying an auxiliary conveyer, hinge members having strap portions secured on the outer sides of the respective plates and having inwardly offset bearing heads, brackets pivotally supporting the bearing heads projecting from said shaft adjacent the outer sides of said bearing heads and having arcuate guide portions in slidable engagement 95 with intermediate portions of said strap members, projections cooperating with the hinge members to embrace the arcuate portions of the brackets, and means for maintaining said engagement. 100

2. In potato diggers, the combination with the upper conveyer shaft of a digger of an extension conveyer comprising side plates carrying an auxiliary conveyer, hinge members comprising strap portions secured on the outer sides of the respective plates and bearing heads positioned inside the planes of said side plates, shaft brackets projecting from said shaft adjacent the outer sides of said bearing heads and having arcuate guide portions substantially radially spaced from said bearing heads in contact with an intermediate portion of said straps, and radially extending means on the straps for slidably interlocking them with said guide portions, said bearing heads being pivotally supported by the shaft brackets. 110

3. In a potato digger, a wheel supported frame, a main conveyer carried by said frame, means for operating said conveyer, an extension conveyer arranged to be readily attached to the digger so as to receive material from said main conveyer, cooperating members upon said frame and said extension conveyer for pivotally mounting said extension conveyer on said frame, slidably interfitting parts on said members for permitting said extension conveyer to be moved into operative position behind said main conveyer, and means for locking said extension 120 125 130

- conveyer in pivotal operative relationship to said main conveyer in all pivotal positions of the extension conveyer, said locking means acting with one of said cooperating members to form a fork-shaped structure for slidably receiving the other of said cooperating members.
4. In a potato digger, a wheel supported frame, a main conveyer carried by said frame, means for operating said conveyer, an extension conveyer arranged to be readily attached to the digger so as to receive material from the main conveyer, cooperating members upon said frame and said extension conveyer for pivotally mounting said extension conveyer on said frame, slidably interfitting parts on said members for permitting
- 5
- 10
- 15
- 20
- 25
- 30
- said extension conveyer to be moved into and out of operative position behind said main conveyer, and guide members for normally holding the extension conveyer in operative position during all pivotal movements of the extension conveyer and for preventing side sway of the extension conveyer, each of said guide members acting in conjunction with one of said cooperating members to form a radially extending fork for embracing a part of the other cooperating member.
- In testimony whereof we affix our signatures.

BARNEY GRONKE.
CHARLES F. CRUMB.
